MACHINE FOR CLEANING HAIR AND SCALP

James Ellis, New York, N. Y.

Application May 1, 1944, Serial No. 533,491

2 Claims. (Cl. 183—62)

This invention relates to new and useful improvements in a machine for cleaning one's hair and scalp and for stimulating the growth of hair.

More specifically the invention proposes an improved device as mentioned which is characterized by a scalp massaging member having tubular tits for engaging the scalp and connecting with a suction inlet. Means is proposed for producing suction through said scalp massaging member so as to draw in the loose dandruff and dandruff loosened during the massaging operation.

The invention proposes a novel and sanitary construction for catching and holding the dandruff drawn through the scalp massaging member.

More specifically, the invention proposes to provide a strainer strip movably mounted across a passage for said suction, and to provide a cover strip movably mounted to cover the used web portions of the strainer strip.

Still further the invention proposes an article as mentioned, which is simple and durable and which may be manufactured and sold at a reasonable cost.

The invention further contemplates numerous forms. In one form it is proposed to provide a portable machine for moving along the floor. In another form it is proposed to provide a portable machine for resting on a table.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevational view of a machine for cleaning the hair and scalp and stimulating the growth of hair, and constructed in accordance with this invention.

Fig. 2 is a fragmentary enlarged sectional view of the scalp massaging member and the immediately adjacent portion of the machine disclosed in Fig. 1.

Fig. 3 is a sectional view taken on the line 3—3 of Fig. 2.

Fig. 4 is a side elevational view of another design of machine for cleaning the hair and scalp and stimulating the growth of hair in accordance with this invention.

The machine for cleaning one's hair and scalp and stimulating the growth of hair, includes a scalp massaging member 10 having a plurality of

10 tubular tits 11 for engaging the scalp while the scalp massaging member is massaged and rubbed on the scalp. Preferably, the member 10 is constructed of rubber or other resilient material. Said massaging member 10 is provided with a suction inlet 12 for supplying suction through the various tubular tits 11. A casing 13 is mounted upon said suction inlet 12 and is formed with a passage 14 for connecting the suction with said inlet 12.

The passage 14 also is connected with a hose 15 which is supported on a floor stand 16. This floor stand 16 is provided with casters for rolling along the floor. A suction pump 18 is mounted 15 on the base portion of the stand 16 and is driven by an electric motor 19, also mounted on said base portion. The suction end of the pump 18 connects with a pipe line 10 which connects with the hose 15. A support arm 21 is mounted on the stand 16 and is of forked construction adapted to receive and hold the massaging member 10, when the latter is not being used.

A strainer strip 22 is movably mounted within the casing 13 across the passage 14. This strainer strip 22 is wound onto rolls or spools 23 and 24. These rolls are housed within cavities 25 formed in the casing 13. The roll 24 is connected with a knob 26 located outside of the casing 13 by which it may be turned for drawing off the 20 strainer strip from the roll 23. The casing 13 is provided with a removable cover 27 which when removed exposes the cavities 25 so that the rolls 23 and 24 may be removed.

The strainer strip 22 is associated with a cover strip 28. This cover strip 28 normally is wound 35 on a roll 29 mounted within another cavity 25 formed in the casing 13. The cover strip 29 extends down the side wall of the passage 14 and engages over and around that portion of the strainer strip 22 which is wound upon the roll 24.

The operation of the device is as follows:

The scalp massaging member 10 is massaged on the scalp. The suction pump 18 draws the dandruff and other particles through the tubular tits 11, and these particles are deposited on the strainer strip 22. It is intended that the hair and scalp cleaning machine be used in barber shops and other public places. It is proposed that for each new customer the barber turn the knob 26 so as to extend a new section of the strainer strip 22 across the passage 14. Automatically the old section of the strainer strip 22 will be covered by the cover strip 28 as the knob 26 is turned for turning the roll 24.

In Fig. 4 a modified form of the invention is

disclosed which is very similar to the prior form, distinguishing merely in the fact that a portable motor driven suction pump 18' is adapted to be mounted on a table 20. The hose 15 connects with the suction inlet 20' of the pump 18'. In other respects this form of the invention is similar to that previously shown and like reference numerals identify like parts in each of the several views.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. In combination with a tube through which air to be filtered is adapted to pass, a casing mounted in said tube and formed with a passage through which the air passes, a strainer strip movably mounted within said casing across said passage for filtering the air passing through said tube, and means for covering the used portions of said strainer strip, said strainer strip being wound on rolls mounted within said casing and

located on opposite sides of said passage so that the strainer strip may be moved across from one side to the other to expose a clean area, said means, comprising a cover strip mounted upon 5 a supply roll mounted within said casing and extending along one wall of said passage and engaging upon one of the rolls supporting said strainer strip.

2. In combination with a tube through which air to be filtered is adapted to pass, a casing mounted in said tube and formed with a passage through which the air passes, a strainer strip movably mounted within said casing across said 10 passage for filtering the air passing through said tube, and means for covering the used portions of said strainer strip, said strainer strip being wound on rolls mounted within said casing and located on opposite sides of said passage so that the strainer strip may be moved across from one side to the other to expose a clean area, said means, comprising a cover strip mounted upon a supply roll mounted within said casing and extending along one wall of said passage and engaging upon one of the rolls supporting said 15 strainer strip, said latter roll being provided with a knob by which it may be manually turned.

JAMES ELLIS.
